UNITED STATES PATENT OFFICE.

RICHARD N. WALTON, OF LOS ANGELES, CALIFORNIA.

RAILWAY-CROSSING.

No. 810,178.

Specification of Letters Patent.

Patented Jan. 16, 1906.

Application filed September 13, 1905. Serial No. 278,343.

To all whom it may concern:

Be it known that I, RICHARD N. WALTON, a citizen of the United States, residing at Los Angeles, in the county of Los Angeles and State of California, have invented new and useful Improvements in Railway-Crossings, of which the following is a specification.

My invention relates to that portion of a railway-crossing where the rails of one track cross those of another track at an angle thereto; and the object thereof is to provide cheap, simple, and efficient means to prevent the usual jar which occurs when the car-wheels on one track cross over the rails of the other track. I accomplish this object by the device described herein and illustrated in the accompanying drawings, by what I will term a "railroad-rail-crossing bridge," in which—

Figure 1 is a plan of a portion of two tracks crossing each other at right angles with my bridge in place where the respective rails cross each other. Fig. 2 is a section on the line 2 2 of Fig. 1. Fig. 3 is a section on the line 3 3 of Fig. 2. Fig. 4 is a perspective view of my improved bridge.

In the drawings the rails 5 and 6 of one track cross the rails 7 and 8 of the other track at right angles thereto. The tread of each rail at its point of intersection with the other rail is grooved transversely to allow for the passage through such groove of the flange of the car-wheels which travel upon the other track. In these flange-channels 10 I provide a bridge 11, which has as many arms 11' as there are channels at such rail-crossing, which arms project from the intersection of such channels a sufficient distance to gradually engage the flange 13 of the wheel 14 and gradually raise it high enough so that the tread 15 of the wheel will be above the tread

of the rail when it reaches the flange-channel at the crossing, thereby preventing the wheel from jarring, as it now does in the ordinary railway-crossings.

In the top surface of my bridge are flange-grooves 12, which keep the flange central in the bridge and prevent the flange from running off the bridge as it crosses the flange-channel of the railroad-rail.

I prefer to make my bridge of heavy spring-steel and have the body or central portion thereof raised slightly above the bottom of the rail-flange channel. The ends of the arms which are tapered rest upon the bottom of the rail-flange channel, as best shown in Fig. 2.

By this construction the tread of the wheel is prevented from being injured as it passes over the flange-channel of the rail and all jar therefrom is likewise avoided.

Having described my invention, what I claim as new, and desire to secure by Letters Patent, is—

A bridge for railway-rail crossings comprising a body having a plurality of resilient tapered arms adapted to fit into the flange-channels of the railway-rail crossing at their intersection, said body being raised slightly above the bottom of the flange-channels, and the ends of the arms resting upon the bottom of the flange-channels and having central grooves in the top of the arms and body.

In witness that I claim the foregoing I have hereunto subscribed my name this 7th day of September, 1905.

RICHARD N. WALTON.
